Specification of Letters Patent. Patented Oct. 29, 1918.

Application filed December 13, 1915, Serial No. 66,521. Renewed January 17, 1918. Serial No. 212,368.

To all whom it may concern:

Be it known that I, ADOLPH BUENZLI, a citizen of the United States, residing at Park, in the county of Knox and State of Tennessee, have invented a new and useful Improvement in Mops, of which the following is a specification, reference being had to the accompanying drawing.

My improvement relates particularly to mops comprising a fiber fabric body, a handle, and means for securing the fiber fabric body to the handle.

The object of the improvement is to provide means for securing the fiber fabric body to the handle, such means being of a construction which is simple and economical and will firmly engage the handle and yet permit detaching the handle, in order that a worn-out fiber fabric body may be detached from a handle and another body attached to said handle.

In the accompanying drawings,

Figure 1 is an elevation of a mop embodying my improvement, portions being broken away;

Fig. 2 is a view looking toward the right in Fig. 1, the fiber fabric body being omitted;

Fig. 3 is a section on the line, 3—3, of Fig. 2, looking upward;

Fig. 4 is a view of the holder or fiber fabric body securing means detached from said body and from the handle and viewed in the same direction as in Fig. 2;

Fig. 5 is a plan looking downward upon the holder as shown in Fig. 4;

Fig. 6 is a side view of the lower end of the handle;

Fig. 7 is a view similar to Fig. 2, the handle being provided with studs in lieu of threads and the ends of the holder wire being bent to form ears to facilitate engagement for releasing the holder from the handle, and the portion of the holder which receives the fiber fabric body being broadened or extended sidewise;

Fig. 8 is a view like Fig. 2, excepting that the lower end of the handle is tapered and the holder socket which embraces the handle is correspondingly tapered.

Referring first to Figs. 1 to 6 inclusive, A is the handle, B is the holder, and C is the fiber fabric body or mass. Surrounding the lower end of the handle are two circumferential screw thread grooves, A¹, of proper pitch to leave spaces between them. The handle is usually made of wood and the grooves, A¹,

separated from each other to leave a spiral rib of wood between the grooves of sufficient width to prevent the chipping or breaking out of said rib. A further reason for thus separating said grooves lies in the fact that the wire coils forming the holder socket, as herein described, are to be separated from each other, and said grooves must be spaced and located to adapt them to receive said coils.

The holder, B, is formed of a single piece of resilient wire and comprises an eye, B¹, which is in the form of an upright ring, the wire paralleling and over-lapping itself at B² across the lower end of the handle along a line transverse to the length of the holder, and each portion of the wire then extending sidewise across the plane of the ring and then spirally around the exterior of the handle, A, in one of the spiral grooves, A¹, thus forming coils, B³. Said coils constitute an elastic and self-adjusting socket for the handle, as hereinafter described. The eye or ring, B¹, surrounds the middle of the fiber fabric body, C, said body extending downward at each side of the eye until its two halves lie against each other in substantially the upright position.

The method of manufacture is as follows:

The handle, A, is formed separately and the two spiral grooves, A¹, cut therein around the lower end. A single piece of wire from which the holder, B, is to be formed is first folded upon itself at the middle so as to produce a narrow U-shape blank, resembling a large, elongated staple. The fiber fabric which is to compose the body, C, is then extended crosswise through the lower portion of this blank. Then the two arms of the blank are bent across said body, whereby the eye, B¹, is formed. Then each arm is bent across the plane of the eye and then spirally away from the eye, whereby two groups of oblique coils, B³, are formed, the coils of one group alternating with the coils of the other group and the coils of one group surrounding and being oblique to an axis which is nearly common with the axis of the other group and which preferably cuts the axis of the eye, B¹, in or at the plane of the eye. For the forming of said coils, a cylindrical mandrel, preferably metal and of approximately the size of the lower portion of the handle is placed into position to permit bending of the two arms of the wire blank around the mandrel at the desired spiral pitch while suitable

mechanism is used for engaging and clamping the portion of the blank forming the eye, B¹.

The mass of the fiber fabric body, C, and 5 the size of the eye, B¹, are so proportioned relative to each other as to cause the wire of the eye to intensely compress said fiber fabric. In forming the coils, B², the wire is so 10 pressed against and around the mandrel as to form said coils to adapt them to firmly engage in the grooves, A¹, of the handle.

When the mandrel has been removed and 15 the eye has been freed from the devices by which it has been held, each group of coils forming the socket moves sidewise parallel to a plane to which the axis of the eye, B¹, is perpendicular. Such movement is due to the resiliency of the portion of the wire forming said eye and to the expansive effort 20 of the portion of the fiber fabric lying within said eye. This tendency on the part of these two groups of coils to move laterally away from a common axial socket line materially increases the engagement between the 25 handle and these coils, it being necessary to bring these groups of coils toward and across each other until approximate common axial alinement is attained before the handle can be entered and screwed downward into position. If the socket coils were made of a 30 pitch to cause said coils to lie in engagement with each other, their lateral pressure on the handle would be largely or altogether eliminated. Separated as shown in the drawings, the two sets of coils are entirely independent of each other and have full freedom 35 for the exertion of such lateral strain.

This lateral pressure of these groups of coils in opposite directions materially supplements the ordinary engagement formed 40 between a screw threaded socket and a screw threaded handle extending into said socket. This added engagement is analogous to applying transverse clamp pressure to the 45 parts of a split, threaded socket surrounding a handle. In practice I have found that such a holder socket formed with only the number of coils shown in the drawings makes ample engagement with the handle 50 for the practical use of the mop, and usually, when it is desired to detach the handle, it is necessary to apply a hand tool at the ends of 55 the wire at the upper portion of the socket to spring the coils outward sufficiently to case their engagement with the handle.

Since this holder socket is composed of 60 two sets of coils having tendency for lateral movement as described, it is a self-adjusting socket adapting itself to variation in the wood of the handle due to wetting and drying. It may be said that this holder socket is a duplex socket composed of two coil groups which are largely or substantially independent of each other. It may 65 also be said that the lower end of the

handle, A, serves as a key to hold the two groups of coils in common axial alinement and that the socket becomes completed by the insertion of the handle. It is also to be observed that bringing the groups of coils 70 into common alinement and then inserting the handle in the socket serves to further tighten the engagement of the fiber fabric body by the eye.

In this connection, it is to be observed 75 that the eye and said coils are so formed that any stress applied to the eye tending to turn the latter in either direction on an axis parallel to the length of the handle tends to tighten the socket coils on the handle. Applying stress to said eye in one direction 80 tends to screw said coils forward and upward on the handle. Applying stress to turn said eye in the opposite direction tends to contract or reduce the diameter of said 85 coils and consequently increases their engagement with the handle. Only applying stress to the ends of the coil wire in the manner already described tends to open or 90 enlarge the coils.

In Fig. 7, the eye, B, is broadened or extended laterally so as to adapt it to surround a broadened fiber fabric body. In the same figure, the spiral grooves, A¹, of the preceding figures are omitted and studs, A², are 95 placed on the handle in such positions as to cause them to stand between the coils of the holder socket when the latter is applied to the handle. In the same figure, the ends of the holder wire are elongated and bent 100 to form ears, B⁴, the purpose of said ears being to facilitate engagement for applying stress to ease or enlarge the holder coils.

The structure shown by Fig. 8 differs only from the structure shown by Figs. 1 and 2 in that the lower end of the handle, A, is tapering and the socket is correspondingly tapered, whereas in Figs. 1 and 2 the lower portion of the handle is of uniform diameter and the socket is correspondingly uni- 110 form.

When the lower end of the handle, A, is thus made tapering it may be more readily entered into the socket without first placing the two coil groups fully into axial alinement. 115

I claim as my invention:

1. In a structure of the nature described, the combination of a fiber fabric body and a holder, said holder comprising an expansive eye and a handle socket consisting of two groups of wire spiral coils, the coils of one group alternating with and movable sidewise relative to the coils of the other group and said groups being supported by 120 opposing portions of the eye, the resiliency of the eye tending to move said groups laterally out of a common axial alinement, substantially as described.

2. In a structure of the nature described, 130

- the combination of a fiber fabric body and a one-piece wire holder, said holder comprising an expansive eye and a handle socket consisting of two groups of wire 5 spiral coils, the coils of one group alternating with and being movable sidewise relative to the coils of the other group and said groups being supported by opposing portions of the eye and the resiliency of the eye 10 tending to move said groups laterally out of common axial alinement, and a handle in said socket, substantially as described.
3. In a structure of the nature described, the combination of a fiber fabric body and a 15 holder, said holder being formed of a single piece of wire and comprising an eye and a socket which is composed of two groups of spiral coils, the coils of one group alternating with and being free from the coils of 20 the other group, the wire slidably over-lapping itself at the junction of the eye and the socket, substantially as described.
4. In a structure of the nature described, the combination of a fiber fabric body and a 25 holder, said holder being formed of a single piece of wire and comprising an eye at the middle of the wire and a socket consisting of spiral coils formed at the ends of the wire, the group of coils on one wire alternating with and being free from the other group, the wire slidably over-lapping itself 30 at the junction of the eye and the socket, and a handle in said socket, substantially as described.
- 35 5. In a structure of the nature described, the combination of a fiber fabric body and
- a holder consisting of a single piece of wire and comprising an eye at the middle of the wire and groups of coils at the ends of the wire together forming a socket, the wire 40 overlapping itself along a line transverse to the length of the holder and between the eye and the coils in such manner as to permit movement of the overlapping portions upon each other for the expansion and contraction 45 of said eye and the movement of said groups of coils into and out of axial alinement with each other, substantially as described.
6. In a structure of the nature described, 50 the combination of a fiber fabric body and a holder consisting of a single piece of wire and comprising an eye at the middle of the wire and groups of coils at the ends of the wire together forming a socket, the group of 55 coils on one end of the wire being movable sidewise relative to the group of coils on the other end of the wire, and the wire overlapping itself along a line transverse to the length of the holder and between the eye and 60 the coils in such manner as to permit movement of the overlapping portions upon each other for the expansion and contraction of said eye and the movement of said groups of coils into and out of axial alinement with 65 each other, and a handle in said socket, substantially as described.

In testimony whereof I have signed my name this 10th day of December, in the year one thousand nine hundred and fifteen.

ADOLPH BUENZLI.

Copies of this patent may be obtained for five cents each, by addressing the "Commissioner of Patents, Washington, D. C."

Correction in Letters Patent No. 1,282,746.

It is hereby certified that the residence of the patentee in Letters Patent No. 1,282,746, granted October 29, 1918, upon the application of Adolph Buenzli, for an improvement in "Mops," was erroneously written and printed as "Park, Tennessee," whereas said residence should have been written and printed as *Park City, Tennessee*; and that the said Letters Patent should be read with this correction therein that the same may conform to the record of the case in the Patent Office.

Signed and sealed this 26th day of November, A. D., 1918.

[SEAL.]

R. F. WHITEHEAD,

Acting Commissioner of Patents.
